UNITED STATES PATENT OFFICE.

GEORGE OSBORN CULVER, OF QUARRYVILLE, NEW JERSEY.

GATE.

SPECIFICATION forming part of Letters Patent No. 657,395, dated September 4, 1900.

Application filed April 28, 1900. Serial No. 14,713. (No model.)

To all whom it may concern:

Be it known that I, GEORGE OSBORN CULVER, a citizen of the United States, and a resident of Quarryville, in the county of Sussex 5 and State of New Jersey, have invented a new and Improved Gate, of which the following is a full, clear, and exact description.

The invention is an improvement in the class of farm-gates which are mounted and 10 adapted to slide on rollers pivoted to posts.

My invention relates to the construction, arrangement, and combination of parts hereinafter described and claimed.

Reference is to be had to the accompanying 15 drawings, forming a part of this specification, in which similar characters of reference indicate corresponding parts in both figures.

Figure 1 is a perspective view of the improved gate closed, showing, in dotted lines, 20 however, a partial open position of the gate; and Fig. 2 is a perspective view of the gate and its supports, illustrating the gate open and standing open transversely of the space between the gate-posts.

25 Three gate-posts are preferably employed, two outer posts 10 and 11 and an intermediate post 13, which is nearer to the post 11, which is the keeper-post, than to the post 10, which is the swing-post for the gate. Under 30 this arrangement of gate-posts a small opening A is provided, especially adapted for use by pedestrians, and a larger opening A', adapted for the passage of vehicles. The post 11 is provided with openings 12, adapted to receive an extension from the gate D, to be 35 hereinafter described. Portions of fence-panels C are illustrated adjacent to the outer gate-posts.

The gate D may be of any approved construction. Usually, however, it consists, as 40 illustrated, of end uprights 14 and 15, intermediate uprights 16, located at one side of the center of the gate structure, and longitudinal rails 17, secured to the said uprights, and 45 one rail 18 extends beyond the end upright 15 farther than the others and is adapted to enter one of the openings 12 in the keeper-post 11.

A pulley 19 is mounted to turn on the intermediate gate-post 13, and this pulley is 50 adapted to engage with the under edge of any

rail 17 of the gate. The rails of the gate are likewise arranged for engagement with a larger pulley 20, and this pulley receives the opposite longitudinal edges of opposing rails 55 17, and the intermediate upright 16 of the gate is provided with a recess 16^a, which recess is adapted to receive the peripheral portion of the large pulley 20 when the gate is opened. The larger pulley 20, which is always in engagement with the gate, is mounted 60 on a spindle 21, attached to a sleeve 22, and this sleeve has sliding movement on a vertical shaft 23, journaled in bearings 24, attached to the inner face of the swing-post 10. 65 This shaft is provided with openings 25, and a pin 26 is passed through the sleeve 22 and one of these openings. The gate may be raised or lowered, according to whether the pin 26, passed through the sleeve 22, enters 70 an upper or a lower opening 25 in the shaft 23. The gate is raised when it is desirable to let small stock pass beneath the gate or when the gate would be otherwise clogged by snow or ice. 75

A suitable latch 27 is provided to hold the gate closed. When the gate is closed, it extends from the post 10 to the post 11, as shown in positive lines in Fig. 1, the forward portion of the gate being supported by the 80 smaller pulley 19, while the rear or heel portion of the gate is supported by the larger pulley 20. Should a pedestrian desire to pass through the gate, the latch 27 is disengaged and the gate is simply pushed back until the 85 forward end upright 15 engages with the smaller pulley 19 or to the position shown in dotted lines in Fig. 1. When, however, a vehicle is to pass, the gate is carried back and at the same time disengaged from the smaller 90 pulley 19 and is carried beyond said pulley and rearward until the larger pulley 20 enters the recess 16^a in the intermediate upright 16. The gate is now turned, so as to be transverse of the space A' between the posts 95 10 and 13, as shown in positive lines in Fig. 2, and, if desired, the gate may be forced forward, so that its forward end will rest upon the ground and its rear portion be supported by the larger pulley 20. If it be desirable to 100 turn short after passing through the gate-opening, the gate is carried around to a posi-

tion parallel with the inner face of the fence-panel C, remaining, however, at all times on the larger pulley 20, and then the gate may be pushed forward until its rear upright 14 5 is practically in alinement with the swing-post 10. The gate may be so balanced and constructed that it may be operated readily, even by a child.

It will be noticed that the gate can be adjusted without the aid of a hammer or wrench and that the spindle 21, upon which the main supporting-pulley 20 is carried, does not extend beyond the front face of the pulley and is therefore not liable to be caught by any 15 object or part of an object passing the gate. It may be also stated that there is no danger of cattle raising the gate or in any manner interfering with its proper action and that as there is little strain upon the gate-posts 20 they may be made very light.

Having thus described my invention, I

claim as new and desire to secure by Letters Patent—

The combination, with a swing or pivot post, of a gate-support comprising a rotatable shaft 25 arranged vertically or parallel to the post, and having a series of holes, a sleeve mounted to slide vertically on said shaft, and having an opening adapted to register with the holes in the sleeve, a pin for securing the 30 sleeve in any adjustment, a pulley mounted rotatably on said sleeve, and a gate mounted slidably on said pulley, as shown and described.

In testimony whereof I have signed my 35 name to this specification in the presence of two subscribing witnesses.

GEORGE OSBORN CULVER.
